UNITED STATES PATENT OFFICE

170,882

TELEVISION RECEIVER

Roger McGunnigle, New York, N. Y.

Application June 11, 1953, Serial No. 25,450

Term of patent 14 years

(Cl. D56—4)

To all whom it may concern:

Be it known that I, Roger McGunnigle, a citizen of the United States of America, residing in the city of New York, in the county of New York, and State of New York, have invented a new, original, and ornamental Design for a Television Receiver, of which the following is a specification, reference being had to the accompanying drawing, forming a part hereof.

Fig. 1 is a perspective view of a television receiver, embodying the new design.

Fig. 2 is a similar view with the receiver shown in an adjusted position.

I claim:

The ornamental design for a television receiver, substantially as shown.

ROGER McGUNNIGLE.
